US0D1018593S

(12) United States Design Patent (10) Patent No.: US D1,018,593 S
(45) Date of Patent: * Mar. 19, 2024

(54) DISPLAY SCREEN OR PORTION THEREOF
WITH ICON

(71) Applicant: GE Precision Healthcare LLC,
Wauwatosa, WI (US)

(72) Inventor: Huei Mian Chiah, Shanghai (CN)

(73) Assignee: GE PRECISION HEALTHCARE
LLC, Wauwatosa, WI (US)

() Term: 15 Years

(21) Appl. No.: 29/787,562

(22) Filed: Jun. 7, 2021

(51) LOC (14) Cl. 14-04

(52) U.S. Cl.

USPC D14/489
